UNITED STATES PATENT OFFICE.

WILLIAM BERTRAM BOLLES, OF MILWAUKEE, WISCONSIN.

ANTIPANIC ACTUATOR FOR DOOR FASTENERS.

Application filed June 1, 1925. Serial No. 33,993.

This invention relates to anti-panic door fastener actuating mechanism for use upon doors, particularly those doors which form the closures for public buildings such as schools, theaters, auditoriums, etc., and which are adapted to permit ready exit from the interior of the building. Such fastener actuating mechanisms are operated by a bar, handle, lever or similar actuating element by means of which the mechanism may be easily operated by any person seeking exit and the operating element is so disposed that the fastener actuating mechanism will be operated by contact of any portion of the body of a person in case a crowd should surge against the door to automatically release the door so that it may swing outward to permit exit.

An object of the present invention is to adapt anti-panic door fastener actuating mechanisms and particularly mechanisms of the type shown in my Patents Nos. 1,383,973 and 1,383,974, granted July 5, 1921, in which the mechanism acts to release the door upon actuation of the operating member in either direction, from the intermediate position in which it is normally held, to operate the knob spindle of the door to which the mechanism is applied to release the latch controlled thereby upon actuation of the operating member in either direction.

A further object is to provide means for locking the actuating mechanism either in a position in which the door is free to swing or in a position in which the door is locked.

With the above and other objects in view, the invention may be said to comprise the fastener actuating mechanism as illustrated in the accompanying drawings, hereinafter described, and particularly set forth in the appended claims together with such variations and modifications thereof as will be apparent to one skilled in the art to which the invention appertains.

Reference should be had to the accompanying drawings forming a part of the specification of which Fig. 1 is an elevation of the fastener actuating mechanism locking toward the inner side of the casing in which the mechanism is housed; Fig. 2 is an edge elevation showing the actuator applied to a door; Fig. 3 is a view similar to Fig. 1 showing a modified form of fastener actuating mechanism; and Figs. 4 and 5 are views similar to Figs. 1 and 2 showing a modified form of fastener actuating mechanism.

Referring to the drawings, the door to which the fastener actuating mechanism is applied is designated by the reference numeral 1 and this door is provided with the usual mortised lock casing 2 which has a latch 3 operated by the usual knob spindle 4. The fastener actuating mechanism is carried by a casing 5 which is adapted to be secured against the inner face of the door and within the casing 5 there are mounted upper and lower slides 6 and 7, which are carried for vertical movement within the casing and project through the upper and lower ends of the casing. The projecting ends of the slides 6 and 7 may have attached thereto fastener bolts which engage suitable keepers in the top of the door frame and in the floor or sill. The lower slide 7 is provided with a laterally projecting portion 8 at its upper end which is recessed to provide a seat for the lower end of a compression spring 9, which bears at its upper end against the upper end of the casing 5. The two slides are in alignment, and the lower slide 7 may be provided with a cylindrical extension 80 which fits within a cylindrical bore in the upper slide 6. A slide actuating lever 11 is mounted in the casing upon the outer side of the lower slide 7, the lever 11 being rotatably mounted upon the wall of the casing 5. The lever 11 is provided, intermediate its ends, with a projecting cylindrical hub portion 12 which fits within a cylindrical recess in a boss 13 formed in the wall of the casing. One end of the lever 11 is connected 90 by a link 14 to a lateral projection 7^a secured to the lower slide 7. The upper slide 6 is provided with a lateral projection 6^a from which is suspended a short link 15 which is connected at its lower end to a long link 16, 95 which extends alongside the slide 7 and is connected intermediate its ends to the end of the lever 11 opposite that to which the link 14 is connected, by means of a pivot 17. The lower end of the link 16 has a rounded 100 bearing portion 18 adapted to engage against the side wall of the casing and has a laterally projecting foot portion 19 which projects into a notch 20 formed in the slide 7. The outer wall of the casing 5 has an outwardly projecting boss 21 in which is mounted a pivot pin 22 which carries the operating lever 23.

The lever 23 has a projection 24 which extends through a slot in the wall of the casing 110 into a slot 25 formed in the slide 7. The slot

25 communicates with the notch 20 and the projection 24 lies between the upper end of the slot 25 and the foot portion 19, of the link 16. The spring 9 acts to force the lower 5 slide 7 downwardly and when the slide 7 is moved downwardly, it acts through the link 14 to turn the lever 11 about its pivot and through the links 15 and 16 to move the upper slide 6 in an upward direction. The slide 10 7 moves downwardly under the action of the spring 9 and at the same time the link 16 moves upwardly until the projection 24, of the operating lever, is engaged by the upper end of the slot 25 and the upper face of the 15 foot 19. When the projection 24, of the operating lever, is so engaged, the lever is held in an intermediate position. If the lever 23 be moved downwardly from this position, the projection will move upwardly, moving 20 the slide 7 up and through the lever 11 and the links, connecting the same to the slides 7 and 6, will move the slide 6 downwardly. If the lever 23 be moved in an upward direction, the links 16 will be moved downwardly 25 and with it the slide 6 and at the same time the lever 11 will be actuated to lift the slide 7. It is thus apparent that if the operating lever 23 be moved in either direction from the intermediate position in which it is normally held by the spring 9, the two slides 6 and 7 will be moved toward each other and locking bolts carried by these slides will be retracted. The projection 24 of the operating lever is preferably rounded and the upper face of the foot 19 and the upper end of the slot 25 are beveled so that the projection 24 may roll and slightly slip upon the beveled faces as the lever approaches the end of its stroke in either direction.

40 The slide 7 is provided with an elongated longitudinal slot 26 through which the knob spindle 4 projects and the hub portion 12 of the lever 11 has an axial socket 27 in which the inner end of the spindle 4 fits. Whenever 45 the operating lever 23 is actuated, a turning movement is imparted to the lever 11 through the link 14 or through the link 16, depending upon the direction in which the lever 23 is actuated, the turning movement of the 50 lever 11 being always in the same direction. The latch operating knob spindles of doors are sometimes arranged to operate the latch when turned in one direction and in some locks the releasing movement of the spindle 55 is opposite that in others. It is obvious that the actuating mechanism above described may be adapted to operate a spindle in a direction opposite that shown in the drawings by merely reversing the connections 60 from the lever 11 to the slides, arranging the links 14 and 16 on the sides of the slide 7 opposite that shown.

When a public building is not being used as a meeting place, it may be desirable to permanently lock certain of the exit doors and

in some instances when certain doors are being constantly used, it may be desirable to lock the door latches and bolts in retracted position so that the doors are free to swing. This may be accomplished by providing 70 spaced holes 28 and 29 in the sides of the boss 21, which are so positioned that they are adapted to register with a hole in the lever 23. When the lever 23 is in a position to hold the actuating mechanism in fastener releasing position and when the lever is in its intermediate position, where the fasteners intermediate position, where the fasteners to receive a padlock, by means of which the actuating mechanism may be locked, either 80 in released position or in door locking position, thus the doors may be rendered free to swing or may be permanently locked until the padlock is removed. In cases where it is desired merely to retain the mechanism either in door fastening or door releasing position, so that the mechanism may be readily released from the inside of the building, this may be done by means of a set screw 30 in the slide 7 below the casing 5, which may be engaged in either of two holes 30^a or 30^b in a plate 31, forming an extension of the casing 5. When the screw 30 is engaged in the upper hole 30^a, the actuating mechanism is retained in door-releasing position and when the screw 30 is engaged in the hole 30^b, the fastener actuating mechanism is held against movement in a direction to release the fasteners. The slide 7 may also be provided 90 with transverse apertures 30^c which are adapted to register with openings 30^d in an extension 5^a of the casing one when the mechanism is in locking position so that the mechanism may be secured in locking position 100 by a padlock and the other when the mechanism is in fastener releasing position.

In Fig. 3 of the drawing, I have shown a modified form of fastener actuating mechanism in which the casing 32, which houses the actuating mechanism, has mounted therein a vertically movable slide 33 which slides in a guideway 34 in the upper part of the casing, movement of the slide 33 in an upward direction being resisted by coil springs 35 interposed between the upper end of the slide 33 and the top of the casing 32. Pivotally mounted in the outer wall of the casing is an actuating lever 37 similar to the lever 11 above described, which has a hub portion 38 journaled in the wall of the casing and an axial socket 39 in which the knob spindle 4 fits, the slide 33 being provided with a longitudinal slot 40 through which the spindle extends. From one end of the lever 37 is suspended a long link 41 which has a rounded bearing portion 42 at its lower end adapted to engage the side wall of the casing and a projecting foot portion 43 which extends laterally from the bearing portion 42. A short link 44 is connected to the opposite 110 120 125 130

end of the lever 37 and to the upper end of an auxiliary slide 45, which has a back-plate 46 engaging the outer wall of the casing. The back-plate 46 lies between the lower end 5 of the slide 33 and the outer wall of the casing and the slide 45 has an inwardly projecting lug 48 beneath the lower end of the slide 33. Between the lug 48 and the side wall of the casing the slide 45 is provided 10 with a spring receiving recess 49 in which is mounted a coil spring 50 which bears at its lower end in the bottom of the recess and has its upper end against a part 51 projecting laterally from the lower end of the slide 33, 15 the part 51 having a horn 51^a projecting into the upper end of the spring. The lug 48, of the auxiliary slide and the foot portion 43 of the link 41, receive between them the projecting portion 24^a of an operating lever 20 similar to that shown in Figs. 1 and 2, the under face of the lug 48 and the upper face of the foot portion 43 being beveled to provide inclined engaging faces for the projection 24^a of the operating lever, as in the 25 modification first described.

When the projection 24^a is moved upwardly, the slide 45 is lifted and rocks the lever 37 through the link 44. When the projection 24^a is moved downwardly, the link 41 is moved in a downward direction and rocks the lever 37 in the same direction as when the projection 24^a is moved upwardly. The spring 35 presses down on the slide 33 and serves to hold the foot portion 43 and the lug 48 both in engagement with the projection 24^a, of the lever, thus holding the lever in its intermediate position and actuation of the lever in either direction, from its intermediate position, serves to rock the lever 37 and turn the knob spindle in a direction to release the latch. The slide 33 may be provided with an inwardly extending projection 53, which may extend into a slot in the door and coat with the door lock mechanism to release the lock whenever the slide 33 is actuated. The slide 33 is always actuated in the same direction regardless of the direction of the movement of the operating lever and the thrust of the operating lever is always transmitted to the slide 33 through the spring 50 regardless of the direction in which the operating lever is moved.

The link 41 may be provided with an extension 54, which extends downwardly from the foot portion 43 through the lower end of the casing and this extension may be provided with a threaded opening 52 adapted to receive a set screw which may be engaged in either of two spaced openings 55 in a plate 56 forming an extension of the casing, the spaced openings 55 being positioned to hold the actuating mechanism either in door releasing position or against movement out of the position in which the fasteners are en-

gaged. The extension 54 of the link 41 may be provided with a transverse aperture 57 which is adapted to register with apertures 58 in an extension 59 of the casing 32 when the mechanism is in locking position so that the mechanism may be secured in this position by means of a padlock. 70

In Figs. 4 and 5 of the drawing, I have shown a modified form of spindle operating door fastener actuator in which the actuator casing 60 is applied to the door 1 in such a manner that the knob spindle 4 projects into the upper end of the casing. The casing 60 has pivoted thereto, an operating lever 61 which is connected by a pivot 62 to a boss 63 projecting from the outer face of the casing, the lever 61 having attached thereto a coil spring 64 which has one end bearing against the inner side of the boss 63 and its opposite end bearing against the outer wall of the casing 60, the spring 64 serving to assist in moving the lever 61 to and in holding the lever 61 in a position substantially midway between its upper and lower limits of movement. The lever 60 has a projection 65 which extends through the front wall of the casing 60, the upper face of the projection 65 being engageable with a slide 66 mounted for vertical movement within the casing and the under side thereof being engageable with a lateral projection 67 at the lower end of a link 68 which is pivoted at its upper end to a lever 69, which is pivoted midway between its ends to the front wall of the casing 60. The end of the lever 69 opposite that to which the link 68 is attached, is connected by a short link 70 with the upper end of the slide 66. When the lever 61 is pushed downwardly, the projection 65 of the lever is raised and lifts the slide 66. When the lever 61 is lifted, the projection 65 thereof, is moved downwardly engaging the projection 67 of the link 68 pulling the link 68 downwardly and rocking the lever 69 in a direction to lift the slide 66 through the connecting link 70. The slide 66 is thus moved in an upward direction, whenever the lever 61 is moved in either direction from its intermediate position. The slide 66 is provided with a spring receiving socket 71 in which is mounted a

compression coil spring 72 which bears at its upper end against the lower end of a vertically movable slide 74. The slide 74 is carried for vertical movement in the casing 60 and is held in its lowermost position by a compression spring 75, interposed between the upper end of the casing and a lateral projection 76 at the upper end of the slide 74. The slide 74 has a projection 77 on the side opposite the projection 76 and this projection 77 is connected by a short link 78 with a lever 79 which has a hub portion 80 which is journaled in a boss 81 formed in

the outer wall of the casing 60 and has a square socket adapted to receive the inner end of the knob spindle 4.

When the lever 61 is moved in either direction from its intermediate position, the slide 66 is moved upwardly and through the cushioning spring 72 which imparts an upward thrust to the slide 74 causing the slide 74 to move upwardly compressing the spring 75 and rocking the knob actuating lever 79 about its pivot to turn the spindle 4 to release the door latch. Thus the knob spindle is always turned in the same direction and is actuated to release the latch by movement of the lever 61 in either direction from its intermediate position, the thrust of the lever 61 in either direction being cushioned by the compression spring 72.

The link 68 may have an integral projection 82 provided with the locking means described in connection with Figs. 1, 2 and 3 for securing the mechanism in locking or door releasing position.

The upper end portion of the slide 66 has an abutment 83 against which the laterally extending lower end portion of the slide 74 is held by the compression spring 72, when the mechanism is in locking position, the abutment 83 serving to maintain the spring 72 under a predetermined initial compression and preventing the spring 72 from reacting against the slide returning spring 75. It is to be understood that by a mere reversal of the arrangement the mechanism shown in Figs. 4 and 5 may be adapted to operate a latch spindle of the opposite hand.

Having thus described my invention, I claim:

1. In a device of the character described, the combination with a door having a latch and a knob spindle for actuating the latch, of an anti-panic door releasing mechanism, comprising a casing adapted to be applied to a door and to receive one end of said spindle, a movable operating member upon the outside of the casing, means for normally holding said operating member in an intermediate position, and means within said casing adapted to be actuated by said operating member when moved in either direction from its intermediate position to turn said spindle.

2. In a device of the character described, the combination with a door having a latch and a knob spindle for actuating the latch, of an anti-panic door releasing mechanism, comprising a casing adapted to be applied to a door and to receive one end of said spindle, a movable operating member upon the outside of the casing, a spindle actuating member within the casing adapted to be actuated by said operating member and yielding means interposed between said operating and spindle actuating members.

3. In a device of the character described,

the combination with a door having a latch and a knob spindle for actuating the latch, of an anti-panic door releasing mechanism, comprising a casing adapted to be applied to a door and to receive one end of said spindle, a movable operating member upon the outside of the casing, means within the casing adapted to be actuated by said operating member to turn said spindle to release the latch, and means for locking said mechanism in positions in which said spindle is held either in latch releasing position or in locking position.

4. In a device of the character described, the combination with a door having a latch and a knob spindle for operating the latch, of a casing adapted to be attached to the face of the door, an actuating member rotatably mounted within the casing, said actuating member having an axial socket to receive the knob spindle, a lever carried by the casing and pivoted on an axis at right angles to the axis of said actuating member, means for normally holding said lever in an intermediate position, and means operated by said lever when the same is actuated in either direction for turning said actuating member.

5. In a device of the character described, the combination with a door having a latch and a knob spindle for operating the latch, of a casing adapted to be attached to the face of the door, an actuating member rotatably mounted within the casing, said actuating member having an axial socket to receive the knob spindle, a lever carried by the casing and pivoted on an axis at right angles to the axis of said actuating member, means for normally holding said lever in an intermediate position, means operated by said lever when the same is moved in one direction from said intermediate position for turning said actuating member in one direction, and means operated by said lever when the same is moved in the opposite direction from its intermediate position for turning said actuating member in the same direction.

6. In a device of the character described, the combination with a door having a latch and a knob spindle for operating the latch, of a casing adapted to be attached to the face of the door, a spindle operating lever having a hub portion journaled in the outer wall of the casing and an axially disposed spindle receiving socket in said hub portion, a slide in said casing, a link connection between said slide and spindle operating lever, and a main operating lever pivoted upon the outside of said casing and having a portion projecting into the casing and engageable with the slide.

7. In a device of the character described, the combination with a door having a latch and a knob spindle for operating the latch,

of a casing adapted to be attached to the face of the door, a spindle operating lever having a hub portion which is journaled in the outer wall of the casing, said hub portion having an axial spindle receiving socket, a main actuating lever pivoted to the casing and having an outwardly extending portion and a portion projecting into the casing, members within the casing positioned to be engaged by opposite sides of the projecting portion of the lever, and operating connections between said members and spindle operating lever.

8. In an anti-panic door releasing mechanism, a casing adapted to be attached to the face of a door, a pair of aligned slides, an actuating member carried by the casing, means within said casing adapted to be operated by said actuating member for moving said slides simultaneously in opposite directions, and a spring interposed between one of the slides and the casing.

9. In an anti-panic door releasing mechanism, a casing adapted to be attached to the face of a door, a pair of aligned slides, a lever pivoted intermediate its ends in the casing, links connecting opposite ends of said lever to said slides, and a spring interposed between one of said slides and the casing.

10. In a device of the character described, the combination with a door having a latch and a knob spindle for actuating the latch, of anti-panic door releasing mechanism, comprising a casing adapted to be applied to a door and to receive one end of said spindle, a movable operating member upon the outside of the casing, means for normally holding the operating member in an intermediate position, a member within the casing connected to the spindle and adapted to be operated by the operating member when the same is moved in either direction from its intermediate position to turn said spindle, and yielding means interposed between said members.

11. In a device of the character described, the combination with a door having a latch and a knob spindle for actuating the latch, of anti-panic door releasing mechanism, comprising a casing adapted to be applied to a door and to receive one end of said spindle, a movable operating member upon the outside of the casing, means for normally holding the operating member

in an intermediate position, a slide within the casing, means interposed between the operating member and slide for moving the slide in the one direction when the operating member is moved in either direction, and means connecting the slide and spindle for operating the same.

12. In a device of the character described, the combination with a door having a latch and a knob spindle for actuating the latch, of anti-panic door releasing mechanism, comprising a casing adapted to be applied to a door and to receive one end of said spindle, a movable operating member upon the outside of the casing, means for normally holding the operating member in an intermediate position, a member within the casing connected to the spindle to turn the same, thrust transmitting means within the casing including a cushioning spring and adapted to transmit the thrust of the operating lever to the member connected to the spindle when the lever is moved in either direction from its intermediate position.

13. In a device of the character described, the combination with a door having a latch and a knob spindle for actuating the latch, of anti-panic door releasing mechanism, comprising a casing adapted to be applied to a door and to receive one end of said spindle, a movable operating member upon the outside of the casing, means for normally holding the operating member in an intermediate position, and yielding means within the casing transmitting the thrust of the operating lever when the same is moved in either direction from its intermediate position to the spindle to turn the same in a given direction regardless of the direction of movement of the operating lever.

14. The combination with a door, of a fastener actuating mechanism secured to the inner side thereof, said mechanism comprising an actuating member and movable fastener actuating members adapted to be operated by said actuating member, and means associated with one of said members for securing said mechanism against actuation either in fastener releasing or in door fastening position.

In testimony whereof, I hereunto affix my signature.

WILLIAM BERTRAM BOLLES.
